(57) **CLAIM**

The ornamental design for a headlight for motor vehicle, as shown and described.

DESCRIPTION

FIG. 1 is a perspective view of a headlight for motor vehicle according to a first embodiment;

FIG. 2 is a front view thereof;

FIG. 3 is a rear view thereof;

FIG. 4 is a right side view thereof;

FIG. 5 is a left side view thereof;

FIG. 6 is a top plan view thereof; and

FIG. 7 is a bottom plan view thereof.

FIG. 8 is a perspective view of a headlight for motor vehicle according to a second embodiment;

FIG. 9 is a front view thereof;

FIG. 10 is a rear view thereof;

FIG. 11 is a right side view thereof;

FIG. 12 is a left side view thereof;

FIG. 13 is a top plan view thereof; and,

FIG. 14 is a bottom plan view thereof.

In the drawings the color black represents color contrast.
